METHOD AND APPARATUS FOR BUILDING
ROADSJoseph H. Mosel, Columbus, Ohio, assignor to The
Jaeger Machine Company, Columbus, Ohio, a
corporation of Ohio

Application April 13, 1936, Serial No. 74,059

23 Claims. (Cl. 94—46)

My invention relates to method and apparatus for building roads. It has to do, more particularly, with a machine which is particularly adaptable to building low cost roads or retreading roads with such materials as bituminous mixes or other relatively low cost materials now commonly used. It relates more particularly to a machine for passing over materials previously applied to the surface to be treated and forming therefrom a complete layer or slab.

One of the objects of my invention is to provide a machine which is adapted to form a road surface from material previously applied in front of the machine on the surface to be treated, the machine being adapted to thoroughly mix the material, effectively spread it across the surface to be covered and to form therefrom a layer or slab of the desired thickness and contour and having straight edges, in one pass over said material.

Another object of my invention is to provide a machine of the type indicated with which it will be possible to use road materials, especially of the bituminous mix type, which will quickly set so as to avoid "picking up" by cars while traffic is maintained, which is made possible because of the fact that a single pass by the machine over the material is all that is necessary to form the completed road surface.

Another object of my invention is to provide a machine for forming low cost roads which will form the complete layer or slab with straight edges without the use of expensive side forms that are set along the edges of the surface to be covered.

Another object of my invention is to provide a machine of the type indicated which is particularly adaptable to spreading of material over an old road bed or over a roughly graded or other rough surface, the apparatus being of such a nature that the longitudinal irregularities in the surface being covered will be practically eliminated in the surface produced by the machine and, consequently, the machine will produce a surface which is very even and which will not be "wavy".

Another object of my invention is to provide a machine of the type indicated which is so constructed that material previously dumped on the surface to be covered will be more thoroughly mixed by a single pass of the machine over the material than with a large number of passes with machines of prior art types.

Another object of my invention is to provide a method and machine which is of such a nature

that it is particularly useful in applying bituminous retreading materials to an old road surface and being of such a type that the "tack coat" may be efficiently applied to the old road surface substantially simultaneous with the application of the retreading material thereto.

In its preferred form my invention contemplates the provision of a machine which is composed of two substantially independent units but which are operatively connected together and which operate in conjunction with each other. One of these units embodies a mixing and spreading unit which thoroughly mixes the material, which has been previously applied to the surface to be covered, and which spreads the material across the surface to be covered. This unit thoroughly mixes the material and effectively spreads it in one pass over the material. This unit preferably embodies a comparatively narrow mixing box in which a plurality of pug mills are disposed and means for gathering in the material and conveying it into the mixing box where it is thoroughly mixed. It also includes a pug mill which is disposed behind the mixing box and extends substantially across the machine which also aids in mixing the material but, in addition, serves to spread it laterally across the surface to be covered.

The second unit is a finishing or molding unit and embodies a pair of longitudinally extending runners of considerable length which carry a finishing member, which takes the form of a strike-off blade, substantially midway between the ends of the runners. This finishing unit is connected to the mixing and spreading unit, the mixing and spreading unit being disposed laterally within the runners, by means of connections which permit the mixing and spreading unit to float vertically relative to the finishing unit. The runners of the finishing unit limit lateral spreading of the material produced by the mixing and spreading unit and, consequently, produce straight edges on the layer of material spread by the machine. The finishing member or strike-off blade carried by the runners operates upon the material previously spread by the mixing and spreading unit and serves to level said material to the proper thickness and to produce the proper contour on the surface of the layer.

This application is a continuation in part of my copending applications Serial No. 753,210, filed November 15, 1934, and Serial No. 759,928, filed December 31, 1934.

The machine is preferably so constructed that as it advances through the material previously

applied to the surface to be covered, it removes the material from certain portions of said surface, applies a "tack coat" to said portions of said surface, and then spreads the material over the "tack coat", all of these operations being accomplished substantially simultaneously.

The preferred embodiment of my invention is illustrated in the accompanying drawings wherein similar characters of reference designate corresponding parts and wherein:

10 Figure 1 is a perspective view of a machine constructed in accordance with the principles of my invention.

15 Figure 2 is a perspective view, more or less diagrammatic, of a portion of the machine illustrated in Figure 1.

Figure 3 is a side elevation of the machine illustrated in Figure 1.

20 Figure 4 is a detail in side elevation of the means for adjusting the wheels which support the mixing and spreading unit.

25 Figure 5 is a plan view of a portion of the machine illustrated in Figure 1 illustrating how the material passes through the mixing and spreading unit.

Figure 6 is a longitudinal section taken substantially through the center of the portion of the machine illustrated in Figure 5.

30 Figure 7 is a detail in longitudinal section illustrating the pug mill disposed at the rear of the mixing box and a baffle plate disposed adjacent thereto which controls flow of material rearwardly from the mixing box.

35 Figure 8 is a transverse section through a runner showing a modification.

With reference to the drawings and particularly to Figure 1, I have illustrated my machine as comprising mainly a mixing and spreading unit 1, and a finishing and molding unit 2. These two units are substantially independent of each other but are operatively connected together and cooperate with each other to produce the finished layer or slab of material. The mixing and spreading unit 1 has its rear end disposed laterally within the finishing or molding unit 2 and extends forwardly ahead of the forward end of said finishing and molding unit, as indicated in this figure.

The mixing and spreading unit

50 The mixing and spreading unit 1 comprises a frame 3 which is suitably fabricated of a plurality of longitudinally extending beams 4 and laterally extending beams 5. The forward end 55 of this frame is supported on a wheel 6 while the rear end thereof is supported on a pair of wheels 7. The rear wheels 7 are not free to turn but the front wheel 6 is a caster wheel which may rotate through an angle of 360 degrees. 60 However, the rear wheels may also swivel and may even be steered, if desired.

I provide means for adjusting the wheels 6 and 7 vertically relative to the frame in order to raise or lower the frame. The means for adjusting the wheel 6 and locking it in adjusted position is illustrated best in Figures 1 and 4. The front wheel 6 is carried by a bifurcated arm 8 which has a pin 9 formed on its upper end that is rotatably mounted in a vertically disposed sleeve 70 10. The sleeve 10 has a rearwardly extending arm 11 integrally connected to its lower end. The rear end of this arm 11 is pivoted to the frame 3 as at 12. A bell crank lever 13 has its forward end pivoted to the upper end of the sleeve 75 10 as at 14. This bell crank lever is pivoted to

a support on the frame 3 as at 15. The lower end of the arm 16 of the bell crank lever has one end of a tension spring 17 connected thereto as at 18. The opposite end of spring 17 is connected to a bracket on the frame 3. Adjacent the upper end of sleeve 10 and integral therewith is an arcuate rack 19. A pinion 20 keyed on shaft 21 (Figure 1) meshes with this rack. One end of the shaft 21 is supported by a support 22 on frame 3 and the other end is supported in a worm and gear unit 23 supported on frame 3. The worm and gear unit 23 is operable by a shaft 24 extending to the rear of the mixing and spreading unit and being rotatable by a hand wheel 25.

It will be apparent that with this mechanism the frame 3 may be adjusted vertically relative to the surface to be covered. The wheel 6 may be adjusted relative to the frame 3 and locked in adjusted position merely by operating hand wheel 25 which operates the worm and gear mechanism 23. This in turn rotates the pinion 20 which meshes with rack 19, carried by sleeve 10, and, consequently, moves the sleeve vertically. When the sleeve 10 is moved vertically the arm 11 which is rigidly secured thereto will swing about the pivot point 12. The tension spring 17 is provided for counterbalancing the weight of the mixing and spreading unit so that the weight of the unit will not cause binding of pinion 20 with rack 19 and to aid in raising the frame on the wheel. It will be apparent that the weight of the mixing and spreading unit will tend to cause the sleeve 10 and the integral arm 11 to swing upwardly about the pivot point 12. However, the tension spring 17 tends to cause the bell crank 24 lever to swing about pivot point 15 and its forward end to swing downwardly which in turn tends to move sleeve 10 downwardly and cause the integral arm 11 to swing downwardly about the pivot point 12. In other words, the spring 17 and associated parts serve to exert a force which opposes and neutralizes the gravity force produced by the weight of the mixing and spreading unit.

The mechanism for vertically adjusting each of the wheels 7 relative to the frame 3 is exactly the same as that just described for adjusting the wheel 6. Furthermore, identical counterbalancing means is associated with each of these wheels. The mechanism for adjusting one of the wheels 7 is operable by a hand wheel 25a while the mechanism for adjusting the other wheel 7 is operable by a hand wheel 25b. It will be apparent that each of the wheels is vertically adjustable independently of the others.

On the front of mixing and spreading unit 1 a pair of plow blades 26 are disposed. These plow blades converge at their forward ends and rearwardly diverge as indicated best in Figures 1 and 2. The plow blades have their rear ends rigidly secured to the foremost transverse beam 5 of the frame 3, as at 27. It will be apparent that these plow blades 26 are disposed in front of the front wheel 6. When the machine moves through the material to be mixed and spread, which has been previously dumped on the surface to be covered, the plow blades 26 clear away a path through said material so that the wheel 6 will always operate on a cleared surface. Consequently, the front wheel will always operate upon a comparatively smooth surface and will not operate on the rough surfaces of the material which the machine is adapted to mix and spread.

Welded to the forward converging ends of the plow blades 26 are a pair of brackets 28. These

brackets have a coupling member 29 pivoted thereto as at 30. The coupling member 29 has a draw bar 31 pivoted thereto as at 32. As indicated, the pivot pin 32 may be disposed in any of the vertically spaced openings 33. A removable pin 34 normally prevents the coupling 29 from pivoting about the pin 30. The machine may be drawn along by a tractor or other power unit connected to the forward end of the draw bar 31. The draw bar will normally be prevented from swinging laterally and, consequently, this will insure that the machine will be drawn along in a straight line and will not wobble from side to side.

15 Gathering wings 35 are disposed on each side of the mixing and spreading unit adjacent the forward end thereof. Each of these gathering wings 35 comprises a longitudinally extending forward section 36 and an inwardly extending rear section 37. The two sections 36 are substantially parallel with each other. They extend from a point slightly forward of the foremost ends of the plow blades 26 to a point slightly rearward of the rear ends thereof. These gathering wings are suitably secured to the forward end of the frame 3 as indicated. It will be apparent that a space 38 is provided between the rear end of each plow blade 26 and the adjacent section 36 of the gathering wing, through which material may pass rearwardly.

As previously indicated, the rear sections 37 of the gathering wings converge towards each other. At their rear ends they are connected to the side walls 39 of what may be termed a mixing box 40. This mixing box 40 is open at its top and bottom and is formed by the walls 39 which are vertically disposed plates that extend longitudinally of the machine and are suitably secured to the frame 3 thereof. The ground or old road surface being covered serves as a bottom for the box 40. It will be apparent that the mixing box 40 is comparatively narrow, being substantially half as wide as the frame 3. Adjacent the forward end of the mixing box 40 a pug mill 41 is disposed. Adjacent the rear end of the mixing box a second pug mill 42 is disposed. Each of these pug mills embodies a rotatable shaft 42a having a plurality of small blades 42b extending radially therefrom. These pug mills are adapted to thoroughly agitate and mix the material that passes rearwardly into the mixer box 40.

Directly behind the pug mill 42 is a baffle plate 43 which is disposed within the rear end of the mixing box 40. This baffle plate has its forward end pivoted at 44 and at each end is provided with adjustable bolts which extend through arcuate slots 45 formed in the side walls 39 of the mixer box 40. This baffle member 43 may be adjusted in any desired inclined position and locked in such position. It is adapted to control and limit movement of the material from the rear end of the mixer box 40. If the material being mixed is of such a type that it passes too freely through the mixing box or if there is only a comparatively small amount of such material, due to the fact that a thin layer is being spread by the machine, the baffle 43 may be adjusted until it is almost vertical in order to retard movement of the material from the mixer box and therefore insure that it will be thoroughly mixed before it leaves the rear end of the mixer box. If there is a large amount of the material in the mixing box, due to the fact that a comparatively thick layer is being spread by the machine, or if the material is of such a type that it does not

freely pass through the mixing box, the baffle member 43 may be set into substantially horizontal position or may even be entirely removed. In other words, the baffle member may be adjusted into various positions to meet various conditions.

On the inner surface of each side wall 39 of the mixing box and at the extreme rear end thereof is disposed a rearwardly and inwardly extending diverting blade 46. Supported on one of the transverse beams 5 of the frame 3 adjacent the rear end of the mixing box 40 is a rudder member 47. This rudder member is pivoted so that it may be swung laterally. The forward end of the rudder extends to a point between the diverting blades 46. The rear portion of the rudder extends rearwardly a considerable distance. This rudder member merely embodies a vertically disposed plate which is of substantially the same height as the side walls 39 of the mixing box. It is provided so that the amount of material which is fed to either side of the surface being covered after it leaves the mixing box, may be controlled and varied at will. As indicated in Figure 1, the rudder 47 may be controlled by a shaft 48 which has its end threaded through a block pivoted to the upper end of the pivot pin 49 of the rudder as at 50. The shaft 48 is connected to a hand wheel 51. By rotating hand wheel 51, the rudder may be rotated into any position desired and locked in adjusted position.

At the extreme rear end of the mixing and spreading unit 1 a third pug mill 52 is disposed. This pug mill is practically the same as the other pug mills but is also adapted to spread the material laterally across the surface to be covered. It will be noted that the pug mill 52 extends entirely across the mixing and spreading unit. The blades of this pug mill 52 are helically disposed and are so arranged that the pug mill comprises right and left-hand sections which feed the material towards the right and left respectively. A plate 52a having its lower edge spaced slightly above the axis of pug mill 52 is provided for keeping the material agitated by said pug mill from flying upwardly.

The pug mills 41, 42 and 52 are all preferably rotated in a counterclockwise direction (Figure 6). It is desirable to rotate the pug mills in this direction in order that they will tend to throw the material forwardly rather than rearwardly which would occur if they were rotated clockwise. By rotating them counterclockwise, more thorough mixing is insured since passage of the material through the mixing box will be delayed. However, they may be rotated clockwise, if desired. The means for rotating these pug mills is indicated best in Figures 1 and 2. I preferably provide a gasoline motor 53 which by means of a sprocket and chain drive 54 drives the pug mill 41. By means of a sprocket and chain drive 55 from the pug mill 41 to the pug mill 42, the pug mill 42 is rotated. Furthermore, by means of shaft 56, which is a continuation of the shaft of the pug mill 42, and a sprocket and chain drive 56a, the pug mill 52 is driven.

I will now describe the operation of this mixing and spreading unit. The material to be mixed and spread is preferably previously dumped on the surface to be covered and may be roughly spread over said surface. The mixing and spreading unit will be drawn over said material by a tractor or other power unit. The front wheel 6 is so adjusted that the lower edges

of plow blades 26 and gathering wings 35 will be lightly contacting with the surface to be covered. The sides of the mixing box will also be lightly in contact with the surface to be covered. The plow blades 26 will first pass through the material and will clear a path for the front wheel 6. These plow blades will spread the material laterally. However, lateral movement of the material will be limited by the sections 36 of the gathering wings 35. The material will pass rearwardly through the openings 38 between the plow blades and the gathering wings and will then be guided inwardly towards the center of the machine and into the forward end of the mixing box 40.

Since the mixing box 40 is comparatively narrow, the material through which the machine advances will be constricted. This is a desirable feature. The material through which the machine passes and which is previously applied to the surface to be covered is usually spread over said surface in a layer which is only a few inches thick. This layer would be difficult to mix because it is so thin unless means were provided for gathering it in and concentrating it into a comparatively narrow space. My machine does this. The material is gathered in by the plow blades 26 and gathering wings 35, being preliminarily mixed by such members, and is fed into the mixing box 40. In other words, the material is constricted so that when it is in the mixing box it will form a comparatively thick layer which may be more thoroughly mixed.

When the material enters the mixing box 40, the first pug mill 41 will violently agitate the material, will break up lumps, and will thoroughly mix the material. The material is forced rearwardly through the mixing box 40 until it reaches the second pug mill 42 where it will again be thoroughly mixed. As previously stated, the baffle member 43 will control the length of time that the material remains in the mixing box. As the material leaves the rear end of the mixing box, the rudder 47 may be adjusted as desired to the amount of material fed to either side. The material will feed rearwardly until it reaches the pug mill 52 which will again remix it but will, in addition, feed the material laterally so that it will be spread across the entire surface being covered.

Thus, the material is thoroughly mixed during one passage of the machine over and through the material. Furthermore, the material is effectively spread across the surface to be covered.

With this machine, the "tack coat" may be easily applied to the surface to be covered substantially simultaneous with the application of the layer of material thereto. It will be noted in Figures 1 and 5 that I have provided a perforated pipe 57 behind and between the plow blades 26. This perforated pipe is adapted to be connected to a source of supply of liquid bitumen or other suitable substance adapted to form the "tack coat". The pipe 57 is of such a length that it will extend across the space cleared by the plow blades 26. It will be apparent that the plow blades clear away a path through the material being spread and mixed. Since the pipe 57 is disposed directly behind blades 26, the "tack coat" will be applied to the surface from which the material has been cleared by the plow blades 26.

I also provide a perforated pipe 58 at each side of the machine. Each of these perforated

pipes 58 extends from the side wall of the mixing box outwardly to a point in line with or past the section 36 of the gathering wing. It will be apparent that the sections 37 of the gathering wings will clear paths at each side of the machine through the material previously applied to the surface to be covered. Since the pipes 58 are disposed immediately behind the sections 37, they will cover the portions of the surface which have been cleared of the material by the section 37 with a "tack coat".

Thus, it will be apparent that the pipe 57 will cover the center portion of the surface to be covered with a "tack coat" while the pipes 58 will cover the lateral portions of the surface to be covered with the "tack coat". The plow blades 26 and the sections 37 of the gathering wings are so arranged relative to each other that the entire surface to be covered will be cleared of the material for a sufficient length of time to enable the "tack coat" to be applied. The pipe 57 and the pipes 58 are so arranged relative to each other that the entire surface will be covered with the "tack coat".

As previously stated, the plow blades 26 clear a path for the front wheel 6 so that this wheel will operate upon the surface to be covered. However, the rear wheel 7 will also operate on the surface to be covered, since the portions 37 of the gathering wings 35 will clear paths for these wheels. It will be noted that the wheels 7 are disposed closely adjacent the rear end of the spreader box 40 and laterally outside of the side walls 39 thereof. Since the material is gathered into the spreading box and the wheels 7 are arranged as indicated, the material will feed back between the wheels, and the wheels will operate upon portions of the surface to be covered which have been clear of the material. Thus, the mixing and spreading unit will be supported on three wheels all of which will operate upon the surface to be covered and not upon the material spread by the machine.

If desired, I may provide a perforated pipe 58a, indicated by the dotted lines in Figure 5, which is located at the forward end of the mixer box 40 for adding bitumen or any other suitable binder to the material in the mixing box.

The finishing and molding unit

The finishing and molding unit 2 comprises a pair of longitudinally extending runners 59. These runners are comparatively long so that they will slide over a rough surface and will bridge the irregularities thereof and, consequently, will not move vertically to any considerable extent. These runners are adapted to serve as side forms to limit spreading of material by the unit 1. They are adapted to form straight edges on the layer or slab produced by the machine. Each runner 59 embodies a vertically disposed plate with a flat runner surface on its lower edge. Its forward edge is upturned as at 60 so that it will not dig into the surface over which it slides.

The runner members are spaced apart sufficiently to permit the rear end of the mixing and spreading unit 1 to be disposed therebetween. They extend forwardly a considerable distance past the rear end of the mixing box 40 and overlap the side walls thereof. Substantially midway between the ends of the runners vertical supports 61 are rigidly secured thereto. The upper ends of these supports 61 are joined together by means of a transversely extending beam 62. Thus, the members 61 and 62 serve to join the two runner

members together. Adjacent the rear ends of the runners a transversely extending beam 63 is provided for joining them together. Thus, the runners will be rigidly held in spaced relation and parallel to each other.

The runner members 59 are adapted to carry a member which finishes the surface produced by the machine. This member is carried substantially midway between the ends of the runners. Since the finishing member is carried by the runners which bridge the irregularities in the surface over which they operate, the irregularities in the rough surface will not be reflected in the surface produced by the machine.

The finishing member carried by the runners comprises a strike-off blade or screed 64. This strike-off blade is suspended from the beam 62 by means of shafts 65, one of which is disposed adjacent each end thereof. Each of the shafts 65 is rotatable by a hand wheel 66 and is connected to the strike-off blade 64 in such a manner that upon rotation thereof the end of the strike-off blade will be moved vertically. This may be accomplished by having the lower end of the shaft threaded into a member carried by the strike-off blade. Thus, either end of the strike-off blade may be adjusted independently of the other. The lower edge of the strike-off blade is provided with any suitable means (not shown) for varying the crown of the surface finished thereby. The mixing and spreading unit 1 is so disposed relative to the finishing and molding unit 2 that the strike-off blade 64 is disposed directly behind the pug mill 52.

The strike-off blade 64 has vertically adjustable gates 67 disposed adjacent each end thereof. These gates 67 are slidably mounted in suitable guides on the strike-off blade for vertical adjustment relative thereto. When the strike-off blade is vertically adjusted the gates 67 will move therewith. However, the gates are also capable of independent vertical adjustment relative to the strike-off blade. To accomplish this a link 68 has its outer end pivotally connected to the upper edge of the gate 67 as at 69. Intermediate its ends the link is pivotally connected to a bracket on the upper edge of strike-off blade 64 as at 70. Its inner end is pivotally connected as at 71 to a block to which the lower end of a shaft 72 is threaded. This shaft 72 is adapted to be rotated by means of a hand wheel 73. It will be apparent that when hand wheel 73 is rotated, the link 68 will pivot about the point 70 and will raise or lower the gate 67 relative to the strike-off blade. The gates at the end of the strike-off blade are provided to permit material to bleed rearwardly past the ends thereof when desired.

At the extreme rear end of each of the runners 59 an adjustable blender wing 74 is disposed. One end of the wing 74 is mounted for vertical movement in a support 75 secured to beam 63. The other end is mounted for vertical movement in a support 76 secured to the rear end of the runner. These blender wings extend outwardly and rearwardly as indicated. Each end of the blender wing may be adjusted by means of a screw adjustment 77. Indicating means 78 is preferably provided for indicating the height of the blender wing. On each support 76 a vertically adjustable gate 79 is disposed in front of the blender wing 74 in order to permit material to bleed out past the runner 59. This gate 79 may be adjusted by means of a screw adjustment 80.

The gates 67 and the blender wings 74 are provided mainly for use when the machine lays the

road surface in two or more courses. When the first course is laid they are not used. However, after the first course is laid and a second course is being laid adjacent thereto, the blender wing at that side where the edges of the two courses meet is used in order to get a perfect joint between the two courses. The gate 67 at that side is raised to permit a quantity of material to feed past the end of the strike-off blade. The blender wing 74 then spreads such material laterally behind the runner member and levels off said material, producing a proper joint between the two courses.

In Figure 8 I show an angle iron 59a attached to the lower surface of the runner. It is so disposed that its vertical flange is substantially flush with the inner surface of the runner. This flange on the angle iron cuts through loose material so that the flat surface of the runner will not ride on such loose material and it assists in gripping the ground to prevent side sway.

The means for connecting the two units together

The mixing and spreading unit 1 is connected to the finishing and molding unit 2 in such a manner that the mixing and spreading unit may move vertically without having any effect whatsoever on the unit 2. In other words, the unit 1 is free to float vertically relative to the unit 2. Although it will be apparent that vertical movement of the mixing and spreading unit 1 will be minimized because of the fact that all the wheels which support it will operate upon the surface being covered rather than upon the material applied to said surface, the surface being covered is sometimes comparatively rough and is usually wavy. Consequently, it is desirable that vertical movement of the mixing and spreading unit resulting from rough and wavy conditions of said surface be precluded from effecting corresponding vertical movement of the strike-off blade carried by the finishing and molding unit. Consequently, as previously stated, I provide connections between the mixing and spreading unit 1 and the molding and finishing unit 2 which permit relative floating movement between these two units.

The main elements for connecting these two units together comprise pull rods 81 disposed at each side of the machine. The rear end of each of these rods is pivotally connected to the upper edge of the runner adjacent the point where the strike-off member is located as at 82. This rod extends forwardly almost to the forward end of the runner at the point where it is connected to the spreading and mixing unit. It is pivotally connected to a shaft 83 which extends laterally from the frame 3 as at 84. The outer end of this shaft 83 is free to move vertically in a slot 85 formed in a bracket 86 secured to the runner. A cushion spring 87 is provided for cushioning vertical movement of the pivot point 84. It will be apparent that as the mixing and spreading unit 1 is drawn along, it will pull along the finishing unit by means of the pull rods 81. Furthermore, it will be apparent that with this connection the mixing and spreading unit may move vertically without affecting the molding and finishing unit.

In order to prevent relative lateral movement between the two units I provide the following structure. Adjacent the forward ends of the runners, rods 88 are disposed at opposite sides of the machine. The inner end of each of these rods is pivotally connected to the wall 39 of the mixing

box as at 88. The outer end of each rod fits into a fork member 90 and has a portion on its end which prevents lateral movement of the end of the rod from the fork. Adjacent the rear end of the frame and at each side thereof an outwardly extending member 91 is disposed. Each of these members is adapted to substantially contact with a bearing plate 92. It will be apparent that the members 91 and 92 and the rods 88 and forks 90 will all cooperate to prevent relative lateral movement between the mixing and spreading unit and the finishing unit. This will insure that the runners will function to produce straight edges on the road. However, it will be apparent that these members will not interfere in any way with the floating action between the two units.

At the rear end of the frame 3 and at each side thereof a bar 93 is pivoted thereto as at 94 for vertical swinging movement. These bars during operation of the machine are normally in the position indicated in Figure 1. When these bars are swung upwardly they are adapted to lie beneath and contact with lugs 95 disposed on beam 72 of the finishing unit. These bars are provided so that the finishing unit may be supported on the mixing and spreading unit for transportation when desired. It will be apparent that the bars may be swung upwardly with their ends beneath lugs 95. Then if the wheels 6 and 7 are adjusted vertically to raise the frame 3 sufficiently, the runners will be raised out of contact with the ground. Both units will then be supported on the wheels 6 and 7 for movement. The forward ends 35 of the runners will be supported on the frame 3 by means of the shafts 83 contacting with the upper ends of the slots 85 in brackets 86 secured to the runners.

The operation of the entire machine

As previously indicated, this machine is particularly useful in mixing and spreading bituminous mixes and forming therefrom a complete layer or slab. In using the machine, rough stone or other suitable material is preferably first roughly spread across the surface to be covered. The machine is then properly adjusted by adjusting the wheels 6 and 7 so that the plow blades 26, gathering wings 35, and the side walls of the mixing box will lightly contact with the surface to be covered. The strike-off blade 64 is adjusted vertically to the proper extent to produce a layer of material of the desired thickness. Then the entire machine is pulled over and through the material by means of the draw-bar 31 which is connected to a tractor or other power unit. The binding medium, such as bitumen, may be spread over the stone by a separate unit before the machine passes over it or may be applied to the material after it enters the mixing box by means of the pipe 58a.

The plow blades 26 will be the first members to strike the material. They spread the material laterally and clear a path for the wheel 6 and for the application of the "tack coat" to the center portion of the surface by means of the pipe 51. The sections 35 of the gathering wings limit the spreading of the material by the plow blades and the sections 37 thereof gather the material inwardly and direct it into the forward end of the spreading box. Also, the portions 37 clear paths in the material so that the wheels 7 may operate on the cleared surface and so that the "tack coat" may be applied to the sides of the surface by means of the pipe 58. As previously stated, the mixing box is comparatively narrow so that the

material will be constricted and will, therefore, be more thoroughly mixed since it will be concentrated into a narrower but deeper mass. The pug mills 41 and 42 will thoroughly mix the material during its passage through the mixing box. After the material leaves the rear end of the mixing box it passes to the pug mill and spreader 52 which spreads it laterally across the surface to be covered. The amount of material supplied to each side of the surface to be covered may be governed by means of the rudder 47. It will be apparent that the material previously applied to the surface to be covered is cleared from the surface, the "tack coat" is applied to the surface, the material is thoroughly mixed and then is respread over the surface, all of these operations occurring substantially simultaneous during passage of the machine through and over the material.

The strike-off blade of the finishing unit is disposed directly behind the pug mill 52. The pug mill again mixes and forces the material beneath the strike-off blade. The strike-off blade levels off the material to the proper thickness and imparts the proper contour thereto. The runners 59 of the finishing unit serve as side forms to limit lateral spreading of the material and to form straight edges on the layer or slab of material produced by the machine. The mixing and spreading unit may move vertically, because of the fact that the wheels 6 and 7 operate on the surface being covered which may be rough, but the vertical movement of this unit will have no effect on the finishing unit which carries the strike-off blade. Consequently, there will be no danger of the irregularities of the surface which is to be covered being reflected in the surface produced by the machine.

It will be understood that in some instances it may not be desirable to apply the "tack coat". Also, it will be understood that this machine is not limited in its application to the mixing and spreading of bituminous material. It may also be used for mixing in place and spreading various other materials, such as stabilized road materials.

The draw-bar 31 is normally not free to pivot about the point 30. However, if it is desired to turn the machine completely around, the pin 34 may be removed to permit the draw-bar to pivot about point 30. This will permit turning of the entire machine in a short radius. Since the draw-bar 31 normally does not pivot about pin 30 and since the wheel 6 is a caster wheel free to rotate completely about the axis of pin 9, the entire machine may be readily maintained on a straight course.

It will be apparent from the above description that I have provided a machine which is adapted to form a road surface from material previously applied in front of the machine on the surface to be treated, either roughly spread across the surface or applied thereto in the form of windrows. The machine will thoroughly mix the material, effectively spread it across the surface to be covered and will form therefrom a layer or slab of the desired thickness and contour and having straight edges, in one pass over said material. Furthermore, with this machine it is possible to apply the "tack coat" substantially simultaneous with the application of the layer of material thereto. This has a distinct advantage over the prior art method wherein it was necessary to first apply the "tack coat", then apply the crushed stone over the "tack coat", the trucks supplying the crushed stone operating over the

"tack coat" and the wheels thereof picking up and removing portions of the "tack coat". Furthermore, with the prior art method the "tack coat" had a chance to set before the crushed stone was applied thereto and especially before the material was mixed.

In using this machine, it is possible to employ road materials, especially of the bituminous mix type, which will quickly set so as to avoid "picking up" by cars while traffic is maintained, which is made possible because of the fact that a single pass by the machine over and through the material is all that is necessary to form the completed road surface.

The machine is of such a nature that it is particularly useful in forming low cost roads, since it will form a complete layer or slab with straight edges without the use of expensive side forms that are set along the edges of the surface to be covered. It is particularly applicable to the spreading of material over an old road bed or over a roughly graded or other rough surface, the machine being of such a nature that the longitudinal irregularities in the surface being covered will be practically eliminated in the surface produced by the machine and, consequently, the machine will produce a surface which is very even and which will not be wavy.

Ordinarily my machine will thoroughly mix and spread the road material in one pass over the material. However, very dense material is sometimes used and when such is the case several passes over the material may be required to thoroughly mix it. If this is the case, I preferably provide an additional element carried by the runner as illustrated in Figures 5 and 6. This element comprises a wing member 96 which is removably bolted to the inner surface of the runner at a point behind the strike-off blade.

This wing member projects inwardly and rearwardly and has its lower edge on a level with the lower edge of the runner. One of these wing members may be provided for each runner.

In using this machine, ordinarily the road is laid in two or more strips or widths. After the first width is laid, when several passes are necessary to mix the material, it is difficult to re-mix the material that lies directly adjacent the edge of the strip already laid. For this reason I provide the member 96 which on the first or subsequent pass over the material will force a portion of the material lying adjacent the edge of the strip already laid inwardly towards the center of the machine and, consequently, it will be more thoroughly mixed. However, on the last pass over the material, the member 96 is entirely removed so that the material will be spread against the adjacent edge of the strip already laid and will be blended therewith.

Although in the specification and claims, I specify that the machine mixes and spreads material previously applied to the surface to be treated, it is to be understood that the machine will mix and spread any relatively loose material disposed along the surface to be treated, whether previously applied or already in place and forming a part thereof, in front of the machine and I intend to cover this by the language used in the claims.

Although in the following claims I use the term "strike-off blade" it will be understood that I intend to cover screed members and other surface finishing members.

Having thus described my invention, what I claim is:

1. A road building machine for operating upon material previously applied to the surface to be treated comprising a mixing and spreading unit, a finishing and molding unit, means for connecting both of said units together in such a manner as to permit them to float relative to each other but to prevent relative lateral movement of said units, said mixing and spreading unit comprising plow blades arranged at the forward end of said unit, a transporting wheel for said mixing and spreading unit disposed behind said plow blades so that said blades will clear a path through the material for the wheel, gathering wings disposed at the forward end of said mixing and spreading unit and being laterally spaced from said plow blades, said gathering wings extending rearwardly and inwardly, a mixing box supported on said mixing and spreading unit, said gathering wings being adapted to direct the material into said mixing box, said mixing box being of substantially less width than the width of the layer of material produced by the machine, a plurality of rotatable mixing members disposed in said mixing box, a baffle member at the rear of said mixing box for controlling passage of material therethrough, a rudder member disposed at the rear of the mixing box for controlling the amount of material fed to each side of the surface to be covered, a rotatable mixing and spreading member disposed behind said mixing box, said member being adapted to spread the material laterally substantially across the surface to be covered, the rear end of said mixing and spreading unit being supported by wheels which operate along paths cleared by said gathering wings, said molding and finishing unit comprising a pair of longitudinally extending runner members of considerable length which are held in spaced parallel relation and which overlap said spreading unit in order to limit lateral spreading of the material, said runners carrying a strike-off blade substantially midway between the ends thereof which strikes off the material spread by the mixing and spreading unit, said strike-off blade having adjustable gates at the ends thereof to permit material to feed back past said strike-off blade, said runners carrying vertically adjustable blender wings which operate upon said material.

2. A road building machine for operating upon material previously applied to the surface to be treated comprising a mixing and spreading unit, a finishing and molding unit, means for connecting both of said units together in such a manner as to permit them to float relative to each other but to prevent relative lateral movement of said units, said mixing and spreading unit comprising plow blades arranged at the forward end of said unit, a transporting wheel for said mixing and spreading unit disposed behind said plow blades so that said blades will clear a path through the material for the wheel, gathering wings disposed at the forward end of said mixing and spreading unit, said gathering wings extending rearwardly and inwardly, a mixing compartment supported on said mixing and spreading unit, said gathering wings being adapted to direct the material into said mixing compartment, said mixing compartment being of substantially less width than the width of the layer of material produced by the machine, a plurality of rotatable mixing members disposed in said mixing compartment, means at the rear end of said mixing compartment for governing the amount of material fed to each side of the surface to be covered, a rotatable mixing and spreading member dis-

posed behind said mixing compartment, said member being adapted to spread the material laterally substantially across the surface to be covered, the rear end of said mixing and spreading unit being supported by wheels which operate along paths cleared by said gathering wings, said molding and finishing unit comprising a pair of longitudinally extending runner members of considerable length which are held in spaced relation and which overlap said spreading unit in order to limit lateral spreading of the material, said runners carrying a strike-off blade substantially midway between the ends thereof which strikes off the material spread by the mixing and spreading unit.

3. A road building machine for operating upon material previously applied to the surface to be treated comprising a mixing and spreading unit, a finishing and molding unit, means for connecting both of said units together in such a manner as to permit them to float relative to each other but to prevent relative lateral movement of said units, said mixing and spreading unit comprising plow blades arranged at the forward end of said unit, gathering wings disposed at the forward end of said mixing and spreading unit, said gathering wings extending rearwardly and inwardly, a mixing compartment carried by said mixing and spreading unit, said gathering wings being adapted to direct the material into said mixing compartment, said mixing compartment being of substantially less width than the width of the layer of material produced by the machine, a rotatable mixing member disposed in said mixing compartment, a rotatable mixing and spreading member disposed behind said mixing compartment, said member being adapted to spread the material laterally substantially across the surface to be covered, said molding and finishing unit comprising a pair of longitudinally extending runner members of considerable length which are held in spaced relation and which overlap said spreading unit in order to limit lateral spreading of the material produced by said unit, said runners carrying a strike-off blade intermediate their ends.

4. A road building machine for operating upon material previously applied to the surface to be treated comprising a mixing and spreading unit, a finishing and molding unit, means for connecting both of said units together in such a manner as to permit them to float relative to each other but to prevent relative lateral movement of said units, said mixing and spreading unit including a mixing compartment, means for directing the material into said mixing compartment as the machine advances, said mixing compartment being comparatively narrow, a rotatable mixing member disposed in said mixing compartment, a rotatable mixing and spreading member disposed behind said mixing compartment, said member being adapted to spread the material laterally substantially across the surface to be covered, said molding and finishing unit comprising a pair of longitudinally extending runner members of considerable length which are held in spaced relation and which overlap said spreading unit in order to limit lateral spreading of material produced by said unit, said runners carrying a strike-off blade intermediate their ends which operates upon the material spread by said mixing and spreading unit.

5. A road building machine for operating upon material previously applied to the surface to be treated comprising a mixing and spreading unit,

a finishing and molding unit, means for connecting both of said units together in such a manner as to permit them to float relative to each other, said mixing and spreading unit including a mixing compartment, a rotatable mixing member disposed in said mixing compartment, a rotatable mixing and spreading member disposed behind said mixing compartment and adapted to spread the material substantially across the surface to be covered, said molding and finishing unit comprising a pair of longitudinally extending runner members of considerable length which are held in spaced relation and which overlap said spreading unit in order to limit lateral spreading of material produced by said unit, said runner members carrying a strike-off blade which operates upon the material spread by said mixing and spreading unit.

6. A road building machine for operating upon material previously applied to the surface to be treated comprising a mixing and spreading unit, a finishing and molding unit, means for connecting both of said units together in such a manner as to permit them to float relative to each other, said mixing and spreading unit including a plurality of rotatable mixing members arranged at longitudinally spaced intervals, said molding and finishing unit comprising a pair of longitudinally extending runner members of considerable length which are held in spaced relation and are so disposed as to limit spreading of material produced by said mixing and spreading unit, said runner members carrying a strike-off blade which operates upon the material spread by said mixing and spreading unit.

7. A road building machine for operating upon material previously applied to the surface to be treated comprising a mixing and spreading unit, a finishing and molding unit, means for connecting both of said units together in such a manner as to permit them to float relative to each other but to prevent relative lateral movement of said units, said mixing and spreading unit comprising plow blades arranged at the forward end of said unit, a transporting wheel for said mixing and spreading unit disposed behind said plow blades so that said blades will clear a path through the material for the wheel, means disposed behind said plow blades for applying a coating of bitumen or other suitable material to the surface to be covered along the path cleared by said plow blades, rearwardly and inwardly extending gathering wings disposed at the forward end of said mixing and spreading unit and being laterally spaced from said plow blades, said gathering wings being adapted to clear the lateral portions of the surface being covered not cleared by said plow blades of material, means disposed behind said gathering wings for applying a coating of bitumen or other suitable material to the portions of the surface cleared thereby, a mixing compartment on said mixing and spreading unit being of substantially less width than the width of the layer of material produced by the machine, said gathering wings being adapted to direct the material into said mixing compartment, a plurality of rotatable mixing members disposed in said mixing compartment, a baffle member at the rear of said mixing compartment for controlling passage of material therethrough, means at the rear of the mixing compartment for controlling the amount of material fed laterally to each side of the surface to be covered, a rotatable mixing and spreading member disposed behind said mixing box, said member being adapted to spread the

material laterally substantially across the surface to be covered, the rear end of said mixing and spreading unit being supported by wheels which operate along paths cleared by said gathering wings, said molding and finishing unit comprising a pair of longitudinally extending runner members of considerable length which are so disposed as to limit lateral spreading of material produced by the mixing and spreading unit, said 10 runners carrying a strike-off blade which operates upon the material spread by said mixing and spreading unit.

8. A road building machine for operating upon material previously applied to the surface to be treated comprising a mixing and spreading unit, a finishing and molding unit, means for connecting both of said units together in such a manner as to permit them to float relative to each other, said mixing and spreading unit comprising plow 20 blades arranged at the forward end of said unit, a transporting wheel for said mixing and spreading unit disposed behind said plow blades so that said blades will clear a path through the material for the wheel, means disposed behind said plow 25 blades for applying a coating of bitumen or other suitable material to the surface to be covered along the path cleared by said plow blades, a second set of blades adapted to clear the lateral portions of the surface being covered not cleared of 30 material by said plow blades, means disposed behind said second set of blades for applying a coating of bitumen or other suitable material to the portions of the surface cleared thereby, said molding and finishing unit comprising a pair of 35 longitudinally extending runner members of considerable length which are so disposed as to limit lateral spreading of material produced by the mixing and spreading unit, said runners carrying a strike-off blade which operates upon the material 40 spread by said mixing and spreading unit.

9. A road building machine for operating upon material previously applied to the surface to be treated comprising a mixing and spreading unit, a finishing and molding unit, means for connecting both of said units together in such a manner as to permit them to float relative to each other but to prevent relative lateral movement of said units, said mixing and spreading unit comprising plow blades arranged at the forward end of said 50 unit, a transporting wheel for said mixing and spreading unit disposed behind said plow blades so that said blades will clear a path through the material for the wheel, gathering wings disposed at the forward end of said mixing and spreading 55 unit and extending rearwardly and inwardly, a mixing compartment supported on said mixing and spreading unit, said gathering wings being adapted to direct the material into said mixing compartment, said mixing compartment being of substantially less width than the width of the 60 layer of material produced by the machine, a plurality of rotatable mixing members disposed in said mixing compartment, means at the rear end of said mixing compartment for governing the 65 amount of material fed to each side of the surface to be covered, a rotatable mixing and spreading member disposed behind said mixing compartment, said member being adapted to spread the material laterally substantially across the 70 surface to be covered, the rear end of said mixing and spreading unit being supported by wheels which operate along paths cleared by said gathering wings, said molding and finishing unit comprising longitudinally extending runner members which are held in laterally spaced relation

and are so disposed as to limit lateral spreading of material produced by said mixing and spreading unit, and a strike-off blade carried by said runner members disposed behind said mixing and spreading unit for operating upon material spread 5 thereby.

10. The method of forming a road surface which comprises roughly spreading an aggregate material over the surface to be covered, applying a binding medium to said material, and then continuously and progressively clearing paths through said aggregate material so as to uncover 10 all portions of said surface and substantially simultaneously applying material to said surface to form a "tack coat", constricting the aggregate 15 material and thoroughly mixing it while it is constricted, and then respreading said material over the portions of said surface to which the "tack coat" has been applied.

11. The method of forming a road surface 20 which comprises roughly spreading an aggregate material over the surface to be covered, and then continuously and progressively clearing paths through said aggregate material so as to uncover 25 all portions of said surface and substantially simultaneously applying material to said surface to form a "tack coat", constricting the aggregate material to a width less than that of the surface to be covered and thoroughly mixing it while it is so constricted, and then respreading said material 30 substantially across the surface to be covered over the "tack coat" previously applied thereto.

12. The method of forming a road surface from aggregate material in place on the surface to be 35 covered which comprises continuously and progressively clearing paths through said aggregate material so as to uncover all portions of said surface and substantially simultaneously applying material to said surface to for a "tack coat", constricting the aggregate material to a width less 40 than that of the surface to be covered and thoroughly mixing it while it is so constricted, and then respreading said material across the surface to be covered over the "tack coat" previously 45 applied thereto in a layer of considerably greater width than the width to which said material was constricted.

13. A road building machine for operating upon material disposed along the surface to be treated in front of the machine comprising a runner unit embodying a plurality of laterally spaced longitudinally extending runner members that slide along the surface to be covered and bridge the irregularities thereof, a mixing and spreading unit carried by transporting means, said mixing and spreading unit including a plurality of rotatable mixing members arranged at longitudinally spaced intervals, said runner members being so disposed as to limit spreading of material produced by said mixing and spreading unit, a strike-off blade carried by said runner unit, said strike-off blade being disposed behind said mixing and spreading unit so that it will operate upon material spread by said unit, and means for 50 tying said units together and preventing substantial relative lateral movement therebetween, said means permitting free vertical movement of the mixing and spreading unit relative to the runner unit so that vertical movement of the 55 mixing and spreading unit caused by the transporting means operating over a rough surface will not be transmitted to said runner unit.

14. A road building machine for operating upon material disposed along the surface to be treated 75

in front of the machine comprising a runner unit embodying a plurality of laterally spaced longitudinally extending runner members that slide along the surface to be covered and bridge the irregularities thereof, a mixing and spreading unit carried by transporting means, said mixing and spreading unit including a mixing compartment, said mixing compartment being of less width than the layer of material adapted to be produced by the machine, means for guiding the material into said compartment as the machine advances, a rotatable mixing member disposed in said mixing compartment, means for spreading said material laterally to a greater width than the compartment as it leaves said mixing compartment, said runner members being so disposed as to limit spreading of material produced by said spreading means, a strike-off blade carried by said runner unit, said strike-off blade being disposed behind said means for spreading the material laterally so that it will operate upon said material, and means for tying said units together and preventing substantial relative lateral movement therebetween, said means permitting free vertical movement of the mixing and spreading unit relative to the runner unit so that vertical movement of the mixing and spreading unit caused by the transporting means operating over a rough surface will not be transmitted to said runner unit.

15. A road building machine for operating upon material disposed along the surface to be treated in front of the machine comprising a runner unit embodying a plurality of laterally spaced longitudinally extending runner members that slide along the surface to be covered and bridge the irregularities thereof, a mixing and spreading unit carried by transporting means, said mixing and spreading unit including a longitudinally extending mixing compartment having a rotatable mixing member disposed therein, said runner members overlapping said mixing and spreading unit in order to limit lateral spreading of material produced by said unit, a strike-off blade carried by said runner unit and disposed so that it will operate upon material spread by said mixing and spreading unit, and means for tying said units together in such a manner as to permit free vertical movement of the mixing and spreading unit relative to the runner unit so that vertical movement of the mixing and spreading unit caused by the transporting means operating over a rough surface will not be transmitted to said runner unit.

16. A road building machine for operating upon material previously applied to the surface to be treated comprising a runner unit embodying a plurality of laterally spaced longitudinally extending runner members that slide along the surface to be covered and bridge the irregularities thereof, a mixing and spreading unit carried by transporting means, said mixing and spreading unit including a mixing compartment having a rotatable mixing member disposed therein, means for directing the material into the mixing compartment as the machine advances therethrough, said runner members overlapping said mixing and spreading unit in order to limit lateral spreading of the material produced by said unit, a strike-off blade carried by said runner unit and disposed so that it will operate upon material spread by said mixing and spreading unit, and means for tying said units together in such a manner as to permit free vertical movement of the mixing and spreading unit relative to the

runner unit so that vertical movement of the mixing and spreading unit caused by the transporting means operating over a rough surface will not be transmitted to said runner unit.

17. A road building machine for operating upon material disposed along the surface to be treated in front of the machine comprising a runner unit embodying a plurality of laterally spaced longitudinally extending runner members that slide along the surface to be covered and bridge the irregularities thereof, a mixing and spreading unit carried by transporting means, said mixing and spreading unit including a mixing compartment, said mixing compartment being of less width than the layer of material adapted to be produced by the machine, means in said compartment for mixing said material, means for spreading said material laterally to a greater width than the compartment as it leaves said mixing compartment, said runner members being so disposed as to limit spreading of material produced by said spreading means, a strike-off blade carried by said runner unit, said strike-off blade being disposed behind said means for spreading the material laterally so that it will operate upon said material, and means for tying said units together and preventing substantial relative lateral movement therebetween, said means permitting free vertical movement of the mixing and spreading unit relative to the runner unit so that vertical movement of the mixing and spreading unit caused by the transporting means operating over a rough surface will not be transmitted to said runner unit.

18. A road building machine for operating upon material previously applied to the surface to be treated comprising a runner unit embodying a plurality of laterally spaced longitudinally extending runner members that slide along the surface to be covered and bridge the irregularities thereof, a spreading unit supported on a plurality of transporting members, blade members disposed in front of all of said members for clearing paths through said material so that all of said members will operate upon the surface to be covered, a strike-off blade carried by said runner unit for levelling off material spread by said spreading unit, and means for tying said units together in such a manner as to permit free vertical movement of the spreading unit relative to the runner unit so that vertical movement of the spreading unit caused by the transporting members operating over a rough surface will not be transmitted to said runner unit.

19. A road building machine for operating upon material previously applied to the surface to be treated comprising a runner unit embodying a plurality of laterally spaced longitudinally extending runner members that slide along the surface to be covered and bridge the irregularities thereof, a mixing and spreading unit carried by transporting means, said mixing and spreading unit including a mixing compartment, a rotatable mixing member disposed in said mixing compartment, means behind said mixing compartment for spreading material substantially across the surface to be covered, said runner members being so disposed as to limit lateral spreading of material produced by said spreading means disposed behind said compartment, a strike-off blade carried by said runner unit for operating upon the material spread by said mixing and spreading unit, and means for tying said units together in such a manner as to permit free

vertical movement of the mixing and spreading unit relative to the runner unit so that vertical movement of the mixing and spreading unit caused by the transporting means operating over a rough surface will not be transmitted to said runner unit.

20. A road building machine for operating upon material disposed along the surface to be treated in front of the machine comprising a runner unit embodying a plurality of laterally spaced longitudinally extending runner members that slide along the surface to be covered and bridge the irregularities thereof, a mixing and spreading unit carried by transporting means, said mixing and spreading unit including a mixing compartment, said mixing compartment being of less width than the layer of material adapted to be produced by the machine, a rotatable mixing member disposed in said mixing compartment, a rotatable mixing and spreading member disposed behind said mixing compartment and adapted to spread the material laterally across the surface to be covered in a layer of considerably greater width than the width of said mixing compartment, said runner members being so disposed as to limit lateral spreading of material produced by said rotatable mixing and spreading member, a strike-off blade carried by said runner unit for levelling off material spread by said rotatable mixing and spreading member, and means for tying said units together and preventing substantial relative lateral movement therebetween, said means permitting free vertical movement of the mixing and spreading unit relative to the runner unit so that vertical movement of the mixing and spreading unit caused by the transporting means operating over a rough surface will not be transmitted to said runner unit.

21. A road building machine for operating upon material previously applied to the surface to be treated comprising a runner unit embodying a plurality of laterally spaced longitudinally extending runner members that slide along the surface to be covered and bridge the irregularities thereof, a mixing and spreading unit carried by transporting means, said mixing and spreading unit including a mixing compartment, means for directing material into said mixing compartment as the machine advances through the material, said mixing compartment being of less width than the layer of material adapted to be

produced by the machine, means for spreading said material laterally across the surface to be covered after it leaves said mixing compartment in a layer of considerably greater width than the width of said mixing compartment, 5 said runner members being so disposed as to limit lateral spreading of material produced by said spreading means, a strike-off blade carried by said runner unit for levelling off material spread by said spreading means, and means for 10 tying said units together and preventing substantial relative lateral movement therebetween, said means permitting free vertical movement of the mixing and spreading unit relative to the runner unit so that vertical movement of the 15 mixing and spreading unit caused by the transporting means operating over a rough surface will not be transmitted to said runner unit.

22. A road building machine comprising a runner unit embodying a pair of laterally spaced 20 longitudinally extending runner members that slide along the surface to be covered and bridge the irregularities thereof, a second unit carried by transporting means, a strike-off member carried by said runner unit, means disposed at a 25 point behind said strike-off member for directing material inwardly towards the center of the machine, and means for tying said units together in such a manner as to permit free vertical movement of the second unit relative to the runner 30 unit so that vertical movement of the second unit caused by the transporting means operating over a rough surface will not be transmitted to said runner unit.

23. A road building machine comprising a 35 runner unit embodying a pair of laterally spaced longitudinally extending runner members that slide along the surface to be covered and bridge the irregularities thereof, a second unit carried by transporting means, a strike-off member carried by said runner unit, means carried by one of said runners at a point behind said strike-off member for directing material inwardly from said runner, and means for tying said units together in such a manner as to permit free vertical movement of the second unit relative to the runner unit so that vertical movement of the second unit caused by the transporting means operating over a rough surface will not be transmitted to said runner unit. 40 45 50
